M. R. CAMORS

ARMATURE SECURING AND CENTERING MEANS

Filed Nov. 29, 1926

Inventor:

Marcel R. Camors.

Marcel R. Camors
Attorney

UNITED STATES PATENT OFFICE.

MARCEL R. CAMORS, OF NEW ORLEANS, LOUISIANA.

ARMATURE SECURING AND CENTERING MEANS.

Application filed November 29, 1926. Serial No. 151,579.

This invention relates to improvements in armature securing and centering means and adapted for use in connection with the ordinary armature core or sleeve combined with

5 the shaft of a typical steam turbo-generator as well as electric motor or electric generators as generally used.

Heretofore it has been the practice, in using small turbine driven generators on 10 steam locomotives, to secure the armature thereof on the shaft of the turbine through the intermediary of a brass sleeve, said sleeve being held in a fixed position by means of a pin passing through the motor shaft and 15 held within the slotted end of the armature sleeve or tube, the other end of said sleeve being engaged by a movable spring-tensioned washer, secured by a movable flanged collar the latter being held in place by a 20 ball or roller bearing and a threaded nut fitted to the end of said motor shaft.

The defects and disadvantages of such an arrangement are evidenced by a loose armature due to the constant wear on the brass 25 tube or sleeve which results in a wobbling armature assuming a somewhat eccentric motion. It then obviously becomes necessary to remove said armature from the core or sleeve causing great loss and inconvenience.

Primarily it is the object of the present invention to cure the above defects by embodying means for mechanically securing the armature sleeve in place in such a manner that same will automatically assume a central or true position with respect to the shaft.

Another object of my invention is to provide a simple and inexpensive means for 40 placing worn armature sleeves on the original motor shaft so that the same will be securely held in a central fixed position, thereby obviating the necessity of re-wiring the armature and renewing the sleeve.

45 Another object of the invention resides in the provision of means for replacing the typical spiral spring and slip collar arrangement for holding the armature sleeve in place, said means embodying a nut threadedly engaging the tapered cone collar contiguous to the concave end of the armature sleeve.

With these objects in view, together with others which will appear as the description 55 proceeds, the invention resides in the novel formation, combination, and arrangement of

parts, all as will be described more fully hereinafter, illustrated in the drawings, and particularly pointed out in the claims.

In said drawings:

60 Figure 1 illustrates a longitudinal central sectional view of my invention as applied to a combined motor and turbine impeller shaft.

Fig. 2 is a slightly modified form of the 65 same.

Fig. 3 is a rear elevation of a conical washer.

Fig. 4 is a side elevation of the same.

Fig. 5 is a front elevation of a slightly 70 modified form of washer; and

Fig. 6 is a side elevation of another slightly modified form of washer.

Referring specifically now to the accompanying drawings, wherein like characters of reference denote similar parts throughout the several views, let 1 denote the motor shaft, which is of well-known construction, said shaft having its end tapered, as indicated at 2, for the reception of a turbine impeller, (not shown) through the intermediary of a key, or similar device, mounted in a keyway 3.

To said shaft 1 is mounted the armature 4, as diagrammatically indicated in Fig. 1, there being interposed therebetween a sleeve or tube 5, the latter having its inner end diametrically slotted, as indicated at 6 for the reception of a pin 7 passing bodily through an aperture 8 in said shaft. As 90 shown in Fig. 2, said shaft 1 is preferably shouldered, as at 9 to receive the abutting end of said sleeve.

The other end, or more properly, the outer end, of said sleeve 1 is threaded, as indicated at 10 for the reception of a nut 12, while its face portion is conically recessed, as indicated at 13, for engagement with a similarly disposed conical projection 14 on the washer 15.

I now direct particular attention to the construction of the washer 15, with special reference to Figs. 1, 3 and 4 of the drawings, wherein it will be observed that I have provided same with a cylindrical body portion 16 and a circumferential flange 17 intermediate of said body portion and said conical projection 14, the purpose and function of which will presently appear.

From the foregoing it is apparent that the 110 interengagement of the conical projection of the washer with the conical recess 13 of

the sleeve 5 firmly secures the latter in alined axial relationship with the shaft 1 and in order to effect a constant engagement of said projection and said recess I provide a helical 5 spring 18, one end thereof encircling the body portion 16 of said washer and abutting the flange 17, while its other end engages a movable collar 19 held in place by means of an ordinary ball thrust of well-known 10 construction.

In the other form shown in Fig. 2 one end of the shaft 1 is secured to the steam turbine impeller by means of the tapered end 20 bearing a keyway 21, similar to the other 15 form. In addition to this said shaft is threaded, as indicated at 22, and is provided with a bearing extension 23, while the other end of said shaft is formed similar to the type illustrated in Fig. 1, with the exception 20 that said shaft is threaded as indicated at 24 to receive a washer 26 having its aperture similarly threaded, as shown in Fig. 5, and thus positive means is provided for holding the sleeve in a central position with 25 respect to the shaft. It will be understood, of course, that in Fig. 2 only a portion of the sleeve 5 is shown and that the washer 26 is retracted to clearly show the conical projection of the washer 26 and conical recess of the sleeve, both of which are identical with the other form. If desired, I may provide 30 said washer 26 with a hexagonal body portion 27, as shown in Fig. 6, to effect easy and rapid application and removal thereof.

The operation of the device is simple in 35 that the washer is arranged with a conical projection to fit the conical recess of the armature sleeve 5 and as said washer is forced inwardly and engages the recess of the sleeve, 40 the latter assumes a true central position with the motor or turbine shaft, causing same to rotate in a true circle thereby avoiding any eccentric motion and securing the armature 4 in true position.

The use of my invention will effect great 45 savings and loss of time, since it is possible to make quick and effective repairs to the present constructions, and in the event my improvement is used at the factory during 50 the primal construction work, parts can

readily be replaced without resort to the use of screw or other press means for removing an armature from the shaft, as is the practice at present.

While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

I claim:

1. The combination with a combined armature and generator or motor shaft having a transverse aperture therein, of a tubular member having one end slotted to aline with the aperture in said shaft, the other end of said member presenting a conical recess and a spring-tensioned element having a conical projection and adapted to constantly abut said conical recess for centering said tubular member on said shaft.

2. The combination with an armature and generator or motor shaft having a transverse aperture therein, of a tubular member encircling said shaft and having one of its ends provided with diametric open-end slots, a pin adapted to engage said tubular member to said shaft and a spring-tensioned element presenting a conical projection and adapted to constantly abut a conical recess in the other end of said tubular member to center the latter about said shaft.

3. The combination with an armature and generator or motor shaft having a transverse aperture therein, of a tubular member encircling said shaft and having one of its ends provided with diametric open-end slots, a pin fitting into said slots and engaging said member to said shaft, the other end of said tubular member presenting a conical recess and a spring-tensioned element having a circumferential flange and a conical projection, said projection being constantly urged into contact with the conical recess to center said member about said shaft.

In testimony whereof I affix my signature.

MARCEL R. CAMORS.
